UNITED STATES PATENT OFFICE.

OTTO EICK, OF ST. LOUIS, MISSOURI.

DESIGN FOR A RUBBER BRUSH.

42,390.

Specification for Design.

Patented Apr. 9, 1912.

Application filed January 13, 1912. Serial No. 671,130. Term of patent 14 years.

To all whom it may concern:

Be it known that I, OTTO EICK, a citizen of the United States, and a resident of St. Louis, in the State of Missouri, have invented a new, original, and ornamental Design for Rubber Brushes, of which the following is a specification, reference being had to the accompanying drawing, forming part thereof.

In the drawings: Figure 1 is a perspective

view of the brush; and Fig. 2 is a side elevation of the same.

I claim:

The ornamental design for a rubber brush, as shown.

OTTO EICK.

Witnesses:

J. A. VALENTIN SCHMIDT,
OTTO GAFFRON.
